UNITED STATES PATENT OFFICE.

JOHN E. LIENAU, OF CORDOVA, NEBRASKA, ASSIGNOR OF ONE-THIRD TO FRANK M: DORSEY, OF CORDOVA, NEBRASKA.

APPARATUS FOR BEADING BOILER-TUBES.

1,186,107.

Specification of Letters Patent.

Patented June 6, 1916.

Application filed February 5, 1916. Serial No. 76,334.

To all whom it may concern:

Be it known that I, JOHN E. LIENAU, a citizen of the United States of America, residing at Cordova, in the county of Seward 5 and State of Nebraska, have invented certain new and useful Improvements in Apparatus for Beading Boiler-Tubes, of which the following is a specification.

This invention relates to new and useful 10 improvements in apparatus for beading or turning over boiler tubes to lock the same upon the flue sheet.

In carrying out my invention I propose to produce an apparatus of this class which 15 may be easily and quickly positioned and tightly sustained in a boiler tube and which is provided with a revoluble carriage having beading rollers thereon arranged to engage with the end of the tube projecting 20 beyond the flue sheet and to contact with the same in such a manner as to turn the edge thereof over onto the flue sheet without danger of breaking or otherwise inflicting injury to either the tube or the flue sheet.

25 It is also my purpose to construct an apparatus of this character wherein the carriage of the beading rollers is engaged by a follower member and compressed thereby, at suitable and desired intervals to advance the 30 carriage to its work.

It is another object of the invention to produce an apparatus of this class which shall embody the desirable features of simplicity in construction, cheapness in manufacture, and ease and accuracy in operation.

With the foregoing objects in view and others which will appear as the nature of the invention is more fully understood, the improvement resides in the construction, 40 combination and arrangement of parts set forth in the following specification and falling within the scope of the appended claim.

The essential features of the invention involved in carrying out the objects above indicated, are necessarily susceptible of embodiment in various forms of construction without departing from the scope of the invention, but certain preferred and practical embodiments are exemplified by the accompanying drawings, in which:

Figure 1 is a side elevation illustrating the application of the improvement, the tube and flue sheet being shown in section, Fig. 2 is an end elevation of the improvement, the 55 beading rollers being omitted, Fig. 3 is a

sectional view on the line 3-3 of Fig. 1, the beading rollers being omitted, Fig. 4 is a horizontal sectional view approximately on the line 4-4 of Fig. 1, Fig. 5 is a sectional view approximately on the line 5-5 of Fig. 1, Fig. 6 is a perspective view of the carriage for the beading rolls, Fig. 7 is a similar view of the follower operating lever, and Fig. 8 is a detail sectional view on a line with the short shafts of the carriage and illustrating the manner in which the beading rolls may be adjusted toward or away from each other to compensate for different diameters of tubes.

Referring now to the drawings the numeral 1 designates the flue sheet and 2 a flue or tube for the sheet.

Before my apparatus is applied the tube 2 has been arranged to project a suitable distance through the opening provided therefor in the flue sheet and has been provided with the outwardly extending bead or bulge to contact with the inner face of the flue sheet.

My improved apparatus includes a stock 30 3 which is in the nature of a tubular member or mandrel and which is of a cross sectional diameter sufficient to permit of the same being readily inserted into the tube.

The stock 3, adjacent its inner end is provided with spaced longitudinally disposed slots and within each of these is arranged a substantially rectangular wedge or jaw member 4. These jaws are pivotally secured to the stock, as indicated by the numerals 5 90 and each of the jaws projects a suitable distance beyond the said inner end of the stock. The jaws, upon their inner edges from their outer ends are beveled and are adapted to be contacted by the cone-shaped head 6 of a 95 bolt 7. This bolt extends through the bore of the stock and is provided with a nut 8. By adjusting this nut against the outer end of the stock the bolt 7 may be moved longitudinally to cause the jaws 4 to be swung outwardly of the stock to cause the teeth of the same to engage with the bore of the tube 2 and consequently hold the apparatus upon the tube, or to permit of the jaws being released from such engagement with the tube. 100

The stock is round in cross section and from its outer end is of a less diameter than that of its inner end, providing a shoulder 9 between the two diameters of the stock. The said outer end of the stock is also, for 110

a suitable distance provided with exterior threads 10.

Arranged upon the reduced diameter of the stock and revoluble thereon is a carriage 11. This carriage includes a head 12 and a tubular body 13. The head is of an approximately rectangular formation and has its opposite ends centrally provided with outwardly extending short shafts or trunnions 14. Upon each of these shafts is arranged a beading roller 15. These rollers are peripherally grooved and are so arranged that the inner flanges 16 thereof are disposed in a line with the inner edge or bore of the tube 2 so that the said flanges will contact with the inner surface of the tube when the main portion of the rollers is acting upon the projecting end of the tube and consequently the said flanges 16 will have a tendency to bulge the tube outwardly or toward the wall of the opening in the sheet 1 through which the tube is projected, thus overcoming any tendency of an inward bulging of the tube during the process of turning over the end of said tube and as a result providing an effective water tight joint between the tube and boiler sheet.

Secured upon the tubular body 13 of the carriage is a ratchet wheel 17 which has its teeth engaged by a spring pressed pawl 18 carried by an operating handle 19. The handle has its headed end bifurcated to straddle the ratchet wheel 17 and its said head provided with openings which find a bearing upon the tubular body 13 to the opposite sides of the said ratchet wheel. The pawl 18 is provided with a stem 20 that passes through an elongated opening in one of the sides of the operating handle whereby the pawl may be manually brought out of engagement with the teeth of the ratchet wheel when desired.

The numeral 21 designates a follower member which is in the nature of a nut and which is screwed on the threads 10 of the stock to contact with the end of the tubular body 13 of the carriage, and when screwed in the direction of the carriage will advance the carriage to its work. The follower member 21 is provided with a rounded periphery, the same being formed with spaced notches 22.

Pivottally secured, as at 23, to one of the sides of the handle 19 is a lever 24. This lever, inward of its pivot, is formed with a curved or arcuate arm 25 that has its end arranged angularly in the direction of the notched periphery of the follower member 21, and the said angular end or lug, indicated by the numeral 26, is adapted to be arranged in one of the notches 22 when the lever is swung in the direction of the handle, to screw the follower member upon the stock and advance the carriage to its work simultaneously with the rotation of the carriage

by the swinging of the handle. The lever 24, at the arcuate portion thereof, and inward of its pivot, is formed with a right angular finger 27, and secured upon the handle is a flat spring 28 which contacts with the offset end of the finger to swing the same to bring its lug or tooth 26 away from the follower member 21, thus permitting the carriage to revolve without advancing the same to its work. This is an important feature of the invention for the reason that should the beading rollers be at all times forced against the end of the tube 2, the constant pressure upon the tube will cause the breakage or the uneven beading or turning over thereof.

In order to permit of the apparatus being employed in connection with tubes of varying diameters as well as to arrange the beading rollers so that their inner flanges will at all times be properly disposed with relation to the inner edge or bore of the tube, I arrange upon the short shafts of the carriage between the head thereof and the said rollers one or a number of washers 29 which also serve to reduce the friction by the contact of the rollers with the end walls of the head of the carriage, and consequently materially assist in the ease of operation. The rollers are detachable, being secured to the short shafts preferably through the medium of cotter pins, as shown in the drawings, and all of the parts of my apparatus are interchangeable.

The stock may be arranged so that the carriage may contact with the shoulder 9 of the stock and thus limit the movement of the carriage in a beading direction, and from the above description, taken in connection with the drawings, the simplicity of the structure, the ease and accuracy with which the bead on the tube will be formed and the operation of the same will, it is thought, be apparent to those skilled in the art to which such invention appertains without further detailed description.

Having thus described the invention, what I claim is:

In an apparatus for beading tubes, the combination with a stock having gripping jaws thereon, of a carriage loosely arranged upon the stock, said carriage including a substantially rectangular head and a tubular body, short shafts upon the opposite ends of the head, beading rollers journaled on said shafts, a ratchet wheel upon the tubular body, a handle member having a bifurcated end loosely arranged on the carriage and straddling the ratchet, a spring pressed pawl carried by the handle for engaging the ratchet, a notched follower member threaded on the stock disposed to contact with the tubular end of the carriage, a lever pivotally secured to the handle, said lever having a curved end terminating in a

tooth disposed to engage with the notches of the follower member, said lever having an offset finger, and a spring member on the handle contacting with the said finger 5 to swing the lever to bring the toothed end thereof away from the follower.

In testimony whereof JOHN E. LIENAU

affixes his signature in the presence of two witnesses.

JOHN E. LIENAU.
